UNITED STATES PATENT OFFICE.

WILBUR D. HOCKENSMITH, OF IRWIN, PENNSYLVANIA.

MINE CAR.

Application filed February 12, 1924. Serial No. 692,242.

This invention relates to mine cars and more particularly to a new and improved form of brake mechanism for such cars.

It includes the use of wooden brake shoes 5 and although it is adaptable to all types of mine cars it will be found particularly advantageous for use on cars of the thin seam type such, for example, as is shown in my Patent Number 1,496,339, granted June 3, 10 1924.

In such cars the maximum capacity, which is of primary consideration, is obtained by extending the floor outwardly beyond the car wheels, the tops of which are inclosed 15 within a housing secured to the floor bottom and extending thereabove. Obviously, the usual method of hanging the brake shoes above the wheels for application to the tops thereof cannot be applied to this type of 20 car without materially reducing its capacity. This is further accentuated by the additional presence of the cumbersome brake rigging, which accompanies this form of brake, above the shoes. While the use of metal 25 brake bands overcomes to some extent the above outlined handicaps, the latter are entirely useless for holding cars on a steep grade and therefore have no practical application.

30 An object of this invention is to provide a brake mechanism for mine cars generally, but particularly adapted to thin seam cars, so constructed and arranged as to be located wholly below the tops of the car 35 wheels in order to provide maximum capacity for a given car.

It is well known to those skilled in the art 40 that the most efficient and practical location for the brake operating lever is at the rear of the car and a further object is to provide, a simple, rugged and improved form of brake operating mechanism which can be easily and surely operated from the rear of the car.

45 A still further object is to provide a strong, rugged brake mechanism which may be easily and quickly removed for repairs and is at the same time cheap to manufacture, easy to install and positive in operation.

50 These and other objects, which will be obvious to those skilled in this particular art, are accomplished by means of this invention, one embodiment of which is shown, 55 by way of example, in the accompanying drawings in which Figure 1 is a side eleva-

tion of part of a mine car having my improved brake mechanism, Fig. 2 is a horizontal longitudinal section on the line 2—2 of Fig. 1, Fig. 3 is a rear elevation showing 60 the brake operating lever, Fig. 4 is a section on the line 4—4 of Fig. 5, and Fig. 5 is a section on the line 5—5 of Fig. 4.

The mine car 6 has the usual wheels 7 and 8 on each side thereof and a housing 9 is 65 provided over each set of wheels. In order to do away with the necessity of cumbersome brake rigging over the wheels of the car, which, as above noted, decreases the capacity thereof, I construct my brake 70 mechanism as follows:

A brake supporting bar or bolt 10 is supported in the side of each housing and midway between the wheels at that side of the car. Two brake shoe supporting arms 11 75 and 12 are supported on the bar or bolt and depend therefrom downwardly between the wheels. In the drawings the arm 11 is shown as provided with a curved hook shaped end 13 which directly embraces the 80 bolt 10. The arm 12 has a similar curved end 14 which is hung over the end 13 of the other arm. Spacers 15 surround the bolt on opposite sides of the brake shoe supporting arms so as to center them on the bolt. 85 The arm 11 has an outwardly turned flange 16 which assists in supporting a brake shoe 17 mounted on the arm and adapted to contact with the periphery of the wheel 8. The arm 12 has a similar, outwardly extending 90 flange 18 and a brake shoe 19 adapted to contact with the periphery of the wheel 7.

A brake actuator is provided between the arms and is shown as being in the form 95 of a roller bar 20 which extends transversely across the car and is mounted in bearings 21 secured to the car bottom, see Fig. 4. The roller bar extends outwardly between the arms 11 and 12 and is provided with flanges 22 and 23 which are adapted to separate the 100 arms 11 and 12 so as to apply the brake shoes to the wheels of the car upon rotation of the roller bar 20.

This rotation of the bar is accomplished 105 by means of a brake rod 24 which is connected to a crank arm 25, formed on the end of the bar 20 and extends rearwardly along the car. The rear end of the brake rod is secured to one arm of a bell crank lever 26, 110 which is shown in the form of a triangular member pivoted between its two arms to a bracket 27 secured to the rear of the car

frame. The bell crank is operated through a connecting rod 29 which is secured thereto and which extends across the rear of the car to a hand brake lever 30 to which it is pivoted. The hand brake lever is pivoted to a bracket 31, secured to the rear of the car, and an ordinary ratchet (not shown) is provided for holding the lever in brake applying position.

10 Adjustment of the brake mechanism is obtained by providing a plurality of perforations 32 in the end of the brake rod 24 by means of which it may be connected to the adjacent arm of the bell crank lever 26 and 15 also by a plurality of perforations 33 by means of which the connecting rod 29 may be secured to the brake lever 30.

It will be understood that the roller bar 20 extends across the entire width of the 20 car and operates brake shoes on the wheels of the other side in the same manner in which it operates the brake shoes 17 and 19. In this way the brakes are simultaneously applied to all four wheels by manipulation of the single hand lever at the rear of the car.

No brake rigging is provided over the 30 wheels so as to reduce the capacity of the car and the entire brake mechanism is conveniently controlled from the rear of the car rather than the side thereof.

In case repairs are needed it is only necessary to remove the bolt 10 in order to remove the brake shoes and their entire supporting structure.

What I claim as new and desire to secure by Letters Patent is:

1. In a mine car, a brake mechanism including a supporting bar, a brake shoe supporting arm having a curved upper end embracing said bar and extending down-

wardly therefrom, a second brake shoe supporting arm embracing the curved upper end of said first arm and extending downwardly from said bar substantially parallel 45 to said first arm, brake shoes supported by said arms and means for actuating said arms so as to operate said shoes.

2. In a mine car, a body portion provided with a wheel housing in the floor thereof, 50 brake mechanism including a supporting bar projecting through a lateral wall of said housing and rigidly secured thereto, a brake shoe supporting arm having a curved upper end embracing said bar and extending 55 downwardly therefrom, a second brake shoe supporting arm embracing the curved upper end of said first arm and extending downwardly from said bar substantially parallel to said first arm, brake shoes supported by 60 said arms and means for actuating said arms to operate said shoes.

3. In a mine car, a body portion having a wheel housing mounted in the floor thereof, 65 brake mechanism including a supporting bar projecting through and secured to the opposite lateral walls of said housing, a brake shoe supporting arm having a curved upper end embracing said bar and extending downwardly therefrom, a second brake shoe 70 supporting arm embracing the curved upper end of said first arm and extending downwardly from said bar substantially parallel to said first arm, spacers on said bar for positioning said arms thereon, brake shoes 75 supported by said arms and means for actuating said arms to operate said shoes.

In testimony whereof, I have hereunto subscribed my name this 9th day of February, 1924.

WILBUR D. HOCKENSMITH.
